COMBINED FLASHLIGHT AND KEY CHAIN

Richard Brody, Sunnyside, N. Y.

Application July 11, 1956, Serial No. 42,215

Term of patent 14 years

(Cl. D48—24)

The figure is a perspective view of a combined flashlight and key chain, showing my new design.

The dotted lines shown in the drawing are for illustrative purposes only.

I claim:

The ornamental design for a combined flashlight and key chain, as shown and described.
